UNITED STATES PATENT OFFICE.

DAVID D. GORDON, OF CHICAGO, ILLINOIS, ASSIGNOR, BY EXPRESS ASSIGNMENT, TO
MICHIGAN MANUFACTURING COMPANY, OF VALPARAISO, INDIANA, A CORPORATION
OF INDIANA.

SWITCH MECHANISM.

Application filed April 19, 1918. Serial No. 2,227,742.

To all whom it may concern:

Be it known that I, David D. Gordon, a citizen of the United States, residing at Chicago, in the county of Cook and State of Illinois, have invented a certain new and useful Improvement in Switch Mechanism, of which the following is a full, clear, concise, and exact description, reference being had to the accompanying drawings, forming a part of this specification.

My invention relates to switch movements and has for its object the provision of a switch movement for electric circuits in which the movable switch element which completes the circuit connection is entirely insulated from the remaining parts of the mechanism.

In the preferred form of the invention I utilize a U-shaped switch element which is so shaped as desired to establish a bridge connection between two stationary contacts, thus to complete the circuit. This switch element is insulatedly mounted so that it may be swung about its mounting and insulating connection is established between said switch element and the remaining portions of the movement so that this switch element or movable switch contact is entirely free from electrical engagement with any of the parts of the mechanism with the exception of the fixed contacts between which it is adapted periodically to establish contact.

This application herein is a divisional application of my application Serial No. 1,14,288, filed January 29, 1918, in which prior application the particular form of carrying out my invention is set forth which I have also selected for illustration herein. In the said co-pending application I particularly claim the switch movement itself. To this present application I am using for illustration the same style of switch movement that is shown and claimed in my said co-pending application. This particular form of movable switch contact and switch movement with which it co-operates is shown in the accompanying drawing, in which

Fig. 1 is a longitudinal sectional view of one form of my switch mechanism as applied to a lamp socket;

Fig. 2 is a sectional view thereof on line 2-2 of Fig. 1;

Fig. 3 is a perspective view of the base plate;

Fig. 4 is a perspective view of two of the operating parts in their disassembled condition;

Fig. 5 is an end view of the right hand element in Fig. 4, and

Fig. 6 shows the parts of the switch movement in a reverse position to that shown in Fig. 1.

The socket illustrated in the drawings consists of the porcelain parts 10 and 11 surrounded and enclosed by the customary shell and cover 18. An insulating connection 14 is provided within which the interior screw threaded contact 15 of the socket is placed, there being also a center contact 16 insulated from the contact 15. The contact 15 terminates in a stationary switch contact 17. There is a co-operating switch contact 18 which is directly connected with the incoming leads. The center contact 16 is then also in the customary manner connected to the remaining of the incoming leads. In order thus to complete the circuit it is necessary to bridge the space between the stationary switch contacts 17 and 18, and this is done through the agency of the U-shaped movable switch contact 19 which is designed to occupy the two positions indicated in Figs. 1 and 6.

This movable switch contact 19 is the one, as stated, which completes the circuit in the device. In order to confine the current only to those parts which are actually necessary to perform the circuit closing and opening functions, I insulatedly mount this switch contact 19 in such a manner that it is not in electrical engagement with any of the parts of the movement, but is only in periodic contact with the switch contacts 17 and 18 whenever the circuit therethrough is completed.

In order to aid the correct understanding of the operations, it will be necessary to describe in detail the switch mechanism which actuates the movable switch contact 19.

This metallic U-shaped movable switch contact is movable by snap action from its positions of circuit closure to circuit opening and from its position of circuit opening to circuit closure. This snap action movement is brought about by means of the structure which will be presently described. This structure together with the element 19 is mounted upon the base plate 20. This base

plate 20 is held in position by the screw 21. This base plate 20 has the upwardly extending arm 22 carrying a seat 23 which projects beyond the confines of the socket. This 5 seat carries the operating lever 24. This operating lever is loosely seated upon the seat 23 and is connected by means of a tension rod 25 with the control element 26 of the movement. Whenever the lever 24 is 10 tilted about its base into any angular position it draws the tension rod 25 to the left. The lever 24 may be tilted into any desired angular position about its base and still effect a movement of the tension member 25 15 to the left (Fig. 1), as readily apparent. The base plate 20 has two side walls 27 and 28 extending upwardly therefrom, which side walls then have inwardly converging extensions 29. The side walls 27 and 20 28 have outwardly extending lugs 30, which lugs carry fiber bearing sleeves 31. The movable switch arm 19 is rotatably seated upon the bearing sleeves 31 so that this switch arm 19 may be entirely 25 insulated from the remaining parts of the operating mechanism.

The control element 26 is shown more clearly in Fig. 4 and this control element co-operates with an operating element 32. 30 The operating element is loosely placed in the movement but confined in its position by having its lugs 33 seated within the slots 34 provided in the control element 26 and being united by means of the spring 35 with the 35 movable switch element 19. The spring is secured to the operating element 32 as shown at 36 and the opposite extremity of the spring is mounted in the insulating lug 37, this insulating lug 37 being mounted upon 40 the outermost extremity of the movable switch element 19, and projecting therethrough as will be most clear from Figs. 1 and 2. Thus the movable switch element 19 is absolutely insulated from all of the 45 remaining parts of the switch movement, including the elements 26, 32, 35, 20, 25, and 24. The left hand extremity (Fig. 1) of the operating element 32 is confined in its position by the plate extension 38 on the one side 50 and by the extensions 29 on the other. The operating element 32 has fingers 39, which fingers co-operate with the right hand end faces (Fig. 1) of the extensions 29 and 38. 55 By referring to Fig. 1, for instance, it is seen that this operating element 32 is held in the position it occupies by having its fingers 39 held in the slots 34 and by having the spring 35 draw its left hand extremity into engagement with the plate extension 38. 60 If it is desired to reverse the position of the movable switch element 19, then the lever 24 is tilted about its base in any suitable manner, or if desired, bodily drawn to the left (Fig. 1), whereupon the tension element 65 25 is moved to the left, this drawing the con-

trol element 26 to the left. The movement of the control element 26 to the left causes the operating element 32 to swing about the right hand edge of the extension 29 in a clockwise direction, this movement continuing until the left hand extremity of the spring 35 has passed beyond the center line of the projections 30. During all this movement the spring 35 has been extended and immediately the left hand extremity of the spring 75 has passed above the projection 30, the movable switch element 19 swings by snap action into the position shown in Fig. 6, also drawing the left hand extremity of the operating element 32 toward the extension 29 80 by snap action. In this movement of the operating element 32, the lower fingers 39 have passed interiorly of the plate extension 38 and have not engaged the right hand face of this plate extension. The minute the pull 85 or tension upon the lever 24 is reduced, however, so that the tension element 25 and the control element 26 may again move to the right, the spring 35 draws these elements to the right, at the same time that it draws the 90 operating element 32 to the right. As this operating element 32 is drawn to the right, the lower fingers 39 which are sliding along the upper face of the plate extension 38 finally pass beyond the right hand extremity 95 of this plate extension and snap into position in a manner similar to that in which the element 32 is shown engaging the extensions 29 in Fig. 1. The position now occupied by the parts is shown in Fig. 6. If then, the 100 lever 24 is again actuated to draw its tension member 25 to the left, the operating element 32 now swings contra-clockwise about the right hand edge of the extension 38 as a pivot carrying the left hand extremity of the 105 spring below the finger 30, whereupon the movable switch element 29 snaps into the position shown in full lines in Fig. 1.

It will thus be seen that the movable switch element 19 is entirely insulated from the remaining parts of the mechanism so that the lever 24 for instance may be of metal if desired, without thereby creating any hazard.

It will be understood, of course, that within the spirit of my invention the movable switch element 19 may be actuated by any properly co-operated switch movement.

Having, however, thus described my invention as being applied to a particular 120 form of movement, what I claim as new and desire to secure by Letters Patent is:

1. A switch movement having a pair of fixed contacts and a movable switch element adapted to bridge said fixed switch contacts 125 to establish circuit connection therewith, a mounting for said switch element having fixed pivot means for one end of said switch element, means for insulating said switch element from said pivot means whereby said 130

element oscillates about a fixed insulated axis, operating means for moving said switch contact from one alternative position to the other, and insulated connecting means interposed between said switch element and said operating means.

3. A switch movement having a pair of fixed contacts and a moveable U-shaped switch element adapted to bridge said fixed switch contact to establish circuit connection therewith, insulating pivotal mountings for said moveable switch contact at the free extremities of its legs whereby it oscillates upon a fixed axis, operating means for moving said switch contact from one alternative position to the other, and insulated connecting means interposed between said switch element and said operating means.

4. A switch movement having a pair of fixed contacts and a moveable U-shaped switch element adapted to bridge said fixed switch contact to establish circuit connection therewith, insulating pivotal mountings for said moveable switch contact at the free extremities of its legs whereby it oscillates upon a fixed axis, operating means for moving said switch contact from one alternative position to the other, and insulated connecting means interposed between the yoke portion of said switch element and said operating means.

5. A switch movement having a pair of fixed contacts and a moveable U-shaped switch element adapted to bridge said fixed switch contact to establish circuit connection therewith, insulating pivotal mountings for said moveable switch contact at the free extremities of its legs whereby it oscillates upon a fixed axis, operating means for moving said switch contact from one alternative position to the other, and insulated connecting means interposed between the yoke portion of said switch element and said operating means.

6. A switch movement having a pair of fixed contacts and a moveable switch element adapted to bridge said fixed switch contacts to establish circuit connection therewith, a pivot of insulating material upon which said moveable switch contact is mounted for oscillation, operating means for moving said switch contact from one alternative position to the other, and insulated connecting means interposed between said switch element and said operating means.

7. A switch movement having a pair of fixed contacts and a moveable switch element adapted to bridge said fixed contacts to establish circuit connection therewith, a mounting for said switch element having a fixed pivot means for one end of said switch element, means for insulating said switch element from said pivot means whereby said element oscillates about a fixed insulated axis, operating means for moving said switch element from one alternative position to the other, connecting means interposed between the other end of said switch element and said operating means, and means for insulating said connecting means from said switch element.

In witness whereof I hereunto subscribe my name this 27th day of March, A. D., 1918.

DAVID D. GORDON.
